CHARLES W. PENDOCK, OF WEST ALLIS, WISCONSIN, ASSIGNOR TO LE ROI COMPANY,
OF WEST ALLIS, WISCONSIN.

INTERNAL-COMBUSTION ENGINE.

Application filed May 24, 1923. Serial No. 641,146.

This invention relates to improvements in internal combustion engines of the type in which the main reservoir for coolant is disposed directly above the engine cylinder, and 5 in which the cooling action is largely one of evaporation, as distinguished from engines in which the reservoir for a considerable part of the coolant is disposed as a usually distinct organization adapted mainly 10 for cooling by radiation. More particularly this invention relates to a detachable head motor of this type in which the circulation of the cooling medium is controlled in a manner adapted to render the cooling of 15 such an engine more efficient.

Water cooled engines have heretofore been provided with detachable heads provided with water jackets in communication with the cylinder water jackets of the engines. 20 So far as I am aware, however, the practice of water jacketing removable engine heads has been confined to radiator-cooled engines and has never resulted in the manufacture of an evaporation-cooled engine in 25 which the water reservoir is disposed above the engine cylinder and is detachable from the cylinder as a unit with the cylinder head or otherwise. It is one of the objects 30 of this invention to provide a detachable jacket section for an engine of the aforesaid evaporation-cooled type and to dispose the securing bolts for such a jacket section (and for the cylinder head as well) internally of the jacket, whereby they may be 35 concealed although they are accessible through the top opening of the jacket.

The unitary construction of a detachable cylinder head and a water reservoir having walls which, when in place, form continuations of the water jacket of the cylinder has obvious advantages in an engine of this type. The cylinder and cylinder water jacket can, if desired, be made to comprise a single casting and the cylinder head and 45 reservoir can also be made of unitary construction so that only a single set of securing bolts is needed to assemble these several parts. When an inspection of a piston head is desired or when it becomes desirable to 50 remove carbon from the interior of the cylinder or from the piston head, it is only necessary to remove the single set of secu-

ring bolts and thereupon the entire superstructure of the engine, including not only the upper part of the water reservoir, but 55 also the cylinder head itself, may be removed separately or as a unit leaving the head of the piston and of the cylinder entirely accessible.

If the jacket and cylinder are constructed 60 as a unit, however, the provision of some means for connecting the cylinder head with the wall of the reservoir is necessary. Inasmuch as it is desirable to provide for free circulation of the cooling liquid upon all 65 sides of the engine cylinder and head, it will be obvious that internal webs, ribs or flanges must be used to connect the cylinder head and reservoir wall in order that these detachable parts may be cast together as a unit 70 to obtain the advantages specified. Presumably, it has heretofore been feared that the provision of such webs or ribs within the reservoir would interfere with the freedom of circulation of the cooling liquid therein. 75 I have made the discovery, however, that properly designed and positioned ribs or webs connecting the reservoir and cylinder head actually promote the circulation of liquid in the reservoir and render the cooling action of such liquid greatly more efficient than has heretofore been the case. 80 Thus, I have succeeded in devising an entirely practical, novel, and greatly improved engine having the cylinder head and reservoir detachable as a unit from the cylinder and cylinder jacket.

While it is one of the principal objects of this invention to provide the unitary detachable cylinder head and reservoir which 90 has been discussed above, I wish nevertheless to make it clear that it is a very important object of this invention so to construct the ribs or webs connecting the cylinder head and reservoir wall as to promote circulation 95 of the cooling liquid through the reservoir and jacket of the engine.

Further objects are to provide a simple structure which will be inexpensive to manufacture and lend itself readily to the casting operation; to provide a novel arrangement of parts so related that their assembly or disassembly can be accomplished with little effort and with the manipulation of a 100

minimum number of bolts or like securing means.

The drawings represent a preferred embodiment of my invention illustrating its 5 application to a single cylinder engine.

In the drawings:

Figure 1 is a section taken on the vertical axis of the engine cylinder and reservoir and indicated at 1—1 in Figure 2.

10 Figure 2 is a section taken on line 2—2 of Figure 1.

Figure 3 is a section taken on line 3—3 of Figure 1.

15 Figure 4 is a section taken on line 4—4 of Figure 1.

Like parts are identified by the same reference characters throughout the several views.

20 The internal combustion engine to which this invention is applied may, in general, be of any desired construction. The engine illustrated includes a cylinder 5 within which a piston 6 is reciprocable. A connecting rod 7 connects the piston to a crank shaft which 25 will be understood to be of ordinary construction. The cam shaft 8 is provided with cams 9 which actuate valve tappet 10 and the stem 11 of valve 12. The valve 12 may represent either the inlet or exhaust valve since 30 it will be understood that one valve will be supplied for each function.

35 The engine illustrated is of the type commonly designated as an L-head engine. In other words, the cylinder head 15 is provided with a laterally projecting recess 16 into which the inlet and exhaust valve open. Recess 16 is preferably wedge-shaped, as shown, and reaching its maximum height 40 immediately above the valves, provides adequate clearance therefor and tapers thence downwardly toward the engine cylinder in order to restrict the size of the recess so that the desired compression of gases may be obtained. Recess 16 terminates at the inclined portion 17 of the cylinder head which 45 is apertured to receive an ordinary spark plug 18.

50 The cylinder 5 is surrounded by a water jacket 20 which will be noted in Figure 1 to be much closer to the cylinder upon one side thereof than upon the other. This construction is adopted not only to increase the water storage capacity of the engine, but also to 55 promote the circulation of the water therein. Where the jacket 20 is closest to the cylinder the comparatively small quantity of water lying between the jacket and the cylinder wall will be heated more highly than will the water at points where the jacket is farther 60 from the cylinder wall. As a consequence, the highly heated water will become lighter and gravity will induce a circulation in the desired direction, the more highly heated water being forced upwardly and replaced 65 by the cooler water. The direction of circu-

lation is indicated by arrows in Figures 1 and 3.

It is preferred that the crank case 14, cylinder 5 and water jacket 20 shall be cast as a unit. Furthermore, in order to enhance 70 the appearance of the engine and to make the casting a comparatively simple operation, the water jacket 20 is preferably extended vertically above the widest portion of the crank case. Ordinarily, the water jacket is 75 extended no lower than the combustion chamber. I have found, however, that the casting of the cylinder block and jacket as a unit is greatly facilitated by extending the jacket wall, as indicated. In addition, this 80 construction derives a further advantage from the fact that increased water storage capacity is provided and the increased area of the jacket facilitates the cooling of water 85 therein.

The water jacket 20 which surrounds cylinder 5 may properly be said to terminate at the margin 21. Throughout its entire periphery, the upper margin of the jacket is 90 preferably disposed in a single horizontal plane, as shown in the accompanying drawings. The upper margin 22 of cylinder 5 is 95 preferably disposed in the same plane. The upper wall 23 of the passages into which the inlet and exhaust valves open may also conveniently lie in this plane. The plane chosen is preferably such that the face of piston 6 will either lie in this plane or will project very slightly thereabove when the piston reaches the highest point of its stroke. 100

Extending vertically above the walls of water jacket 20 and in registry with such walls are the walls of the reservoir 25. The reservoir may comprise a boxlike casting 105 provided at intervals about its lower margin with ears 26 which register with the ears 27 of the water jacket and which are apertured as at 28 to receive securing bolts or cap screws. These ears will be provided in sufficient number so that when a bolt or cap 110 screw is passed through each of said ears and is turned down to tightness, the entire reservoir 25 will be rigidly secured to jacket 20. Suitable gaskets of shellacked paper or 115 other well known material may be interposed between these castings, if desired, to prevent leakage.

At one side of the reservoir 25, a recess 29 is provided leading to the inclined wall 17 120 within which the spark plug 18 is threaded. This recess is so constructed as to permit ready access to the spark plug and at the same time to maintain the plug in proper relation to the combustion chamber of the 125 engine without seriously interfering with the circulation of cooling fluid about said chamber. The inclined wall 17, in fact, not only constitutes a part of the wall of the reservoir but also constitutes a part of the 130 cylinder head 15 which is provided with

marginal portions 30 extending downwardly into registry with the upper margin 22 of the cylinder. The apertured ears 26' upon either side of cylinder head 15 preferably register with corresponding ears 27' formed upon the cylinder in order that the cylinder and cylinder head may be bolted directly together.

Extending transversely across the cylinder head 15 are two ribs or webs 31 and 32. As has previously been suggested, the cylinder head and reservoir comprise an integral casting and the webs or ribs 31 and 32 are integrally connected not only with the cylinder head but with the walls of reservoir 25. Rib 31 is preferably made sufficiently long to connect with two opposite ears 26. Rib 32 may be similarly constructed or may, as shown, terminate in the ears 26' from which branch divergent and subordinate ribs 33 connecting the ears 26' with symmetrically disposed ears 26 on the reservoir. Other ribs 34 converge from other ears 26 to an intermediate portion of rib 32 and are integral with rib 32 and with the cylinder head 15. Thus a very rigid system of integral braces is provided within the reservoir for the purpose of making the cylinder head a strong and easily handled unit with the reservoir.

As has previously been indicated, however, the particular arrangement of the bracing ribs is very important. If these ribs were improperly disposed within the reservoir, they might seriously interfere with water circulation therein. They might, for example, obstruct the flow of water from the reservoir down into the water jacket of the cylinder to an extent such that the water would circulate within the reservoir and comparatively little exchange of water between the reservoir and the water jacket would occur. Under such circumstances, the engine would be inadequately cooled. The placement of ribs in the engine disclosed herein has been worked out with a view to avoid this contingency by insuring that such circulation as occurs will occur through both the reservoir and the water jacket.

Obviously, the greatest heat in an internal combustion engine is developed in that portion of the combustion chamber to which the gases are confined during the initial period of combustion. Thereafter this heat is dissipated through the walls of the combustion chamber and is further reduced by the expansion of the gases which follows piston movement.

In an engine of the type herein disclosed in which the gases at the time of their highest compression are substantially confined to the cavity 16 in cylinder head 15, it will be clear that the portion of the cylinder head immediately above said cavity will be the most highly heated part of the

engine. Therefore, the water or other cooling liquid immediately above the cylinder head will be more highly heated than will the water in other parts of the device. As a matter of fact, it is usual for the water above those portions of the cylinder head which are traversed by ribs 31 and 32 to be in a violent state of ebullition. Where ribs such as those shown at 31 and 32 are not present, there is a decided tendency for this highly heated body of water to be displaced by water coming from the other side of the reservoir and a circulation local to the reservoir may be set up without materially affecting the water in the jacket proper. I have found, however, that where the transverse ribs 31 and 32 are used, such ribs will interfere with any circulation of water tending to come from the opposite side of the reservoir and, as a consequence, the water which displaces the highly heated coolant over these portions of the cylinder head will come up beside the cylinder head from the jacket space therebeneath. To replace the water which is thus caused to rise through the relatively narrow jacket spaces at the left of Fig. 1, a down current occurs in the relatively wide jacket spaces at the right of Fig. 1. The arrows indicate in general the direction of flow. Thus the entire body of water contained in the jacket and reservoir is maintained in constant circulation throughout a definitely prescribed path, and cooling is accomplished more effectively than has heretofore been possible.

The ribs 31 and 32 may be said to have the function of preventing the short circuiting of the desired flow of current since they tend to force water moving downwardly in the reservoir at the right of Fig. 1 to continue on downwardly through the water jacket before they move upwardly past the highly heated cylinder head surfaces at the left of Fig. 1.

I claim:

1. The combination with an evaporation-cooled internal combustion engine having a cylinder and a jacket, of a reservoir unit provided above the normal level of coolant with an opening affording free communication with the atmosphere and, removably connected with said jacket in communication with the space between the jacket and cylinder, and a removable cylinder head connected with said reservoir unit for attachment and removal therewith.

2. The combination with an internal combustion engine having a jacketed cylinder, of a detachable unit including integrally a head for said cylinder, a set of reservoir walls adapted to register with the jacket of said cylinder and to provide a continuation of said jacket opening exteriorly to the atmosphere above the normal level of coolant, and means connecting said walls and head.

3. An internal combustion engine including a cylinder, a jacket about said cylinder and spaced therefrom, a cooling reservoir section adapted to register with said jacket and to constitute a continuation thereof open at its top, and a cylinder head rigidly interconnected with said reservoir section and constituting a unit therewith.

4. An internal combustion engine including a cylinder, a jacket about said cylinder and spaced therefrom, a cooling reservoir section adapted to register with said jacket and to constitute a continuation thereof open at its top, a cylinder head rigidly interconnected with said reservoir section and constituting a unit therewith, and means accessible through the open top of said reservoir section for securing the unit comprising said section and said cylinder head to the jacket and the cylinder.

5. An internal combustion engine including a cylinder wall and a jacket wall, terminating in a common plane, and comprising a unit, in combination with a removable unit comprising a cooling reservoir section adapted to register with said jacket and provided with an opening to the atmosphere rendering its interior portions accessible, and a cylinder head rigidly connected with said reservoir section, together with means accessible through the opening of said reservoir section for removably securing said units together.

6. An internal combustion engine of the evaporation-cooled type, said engine comprising a reservoir jacket constructed in sections separably joined circumferentially, a cylinder disposed within the lower section of said reservoir jacket and rigidly connected therewith, and a cylinder head disposed in the upper section of said reservoir jacket and rigidly connected therewith to comprise a unit, said head being adapted to be operatively joined to said cylinder when said sections are secured together, means to impede circulation relatively more upon one side of said head and cylinder within the reservoir jacket section than upon the other side thereof, and said head being so formed as to present a greater heat area upon that side in which circulation is more impeded whereby to promote an upward circulatory flow above said head and a downward circulatory flow on the less impeded side of said reservoir jacket.

7. A combination with an engine crank case and cylinder operatively connected therewith, of a jacket section connected directly with said crank case and encircling said cylinder, a reservoir section removably joined circumferentially to said jacket section, and a head for said cylinder connected with said removable reservoir section to comprise a unit therewith and adapted to be fitted operatively to said cylinder when said

reservoir section is joined to said jacket section, said reservoir section being open at its top to the atmosphere whereby to promote the evaporation cooling of a circulatory medium in said reservoir jacket section. 70

8. An internal combustion engine comprising the combination of an engine cylinder open at the top, of a water jacket disposed about said cylinder and open at its top, a reservoir comprising an upward extension of said jacket and open at its bottom and top for connection with said jacket and for free communication with the atmosphere, and a cylinder head constructed integrally with said reservoir and adapted to fit 75 operatively upon said cylinder when said reservoir is positioned with reference to said jacket, said head having a heated surface eccentrically disposed with reference to said reservoir and adapted by the promotion of upward flow above said head to promote circulation through said reservoir and said jacket. 80

9. An internal combustion engine comprising the combination of an engine cylinder open at the top, of a water jacket disposed about said cylinder and open at its top, a reservoir comprising an upward extension of said jacket and open at its bottom and top for connection with said jacket and for free communication with the atmosphere, 95 and a cylinder head constructed integrally with said reservoir and adapted to be attached to said cylinder when said reservoir is positioned with reference to said jacket, said head being eccentrically disposed with reference to said reservoir and adapted by the promotion of upward flow above said head to promote circulation through said reservoir and said jacket, said head and said reservoir being interconnected by ribs so 100 disposed with reference to said head as to direct a circulation current throughout said reservoir and jacket.

10. An evaporation-cooled engine comprising the combination of a reservoir jacket open at its top and comprising vertically superimposed sections separably joined circumferentially, of a cylinder disposed within the lower of said sections open at its top, a cylinder head connected with the upper of said sections to comprise a unit for removal therewith and adapted for operative connection with said cylinder when said sections are operatively joined, said head having a surface disposed within the upper of said sections and adapted to be highly heated when said engine is in operation, and ribs connecting said head with the upper of said sections, baffle means spaced to include a highly heated area of said head and joined 115 beyond said head to provide openings affording access to said area from portions of the jacket spaced immediately therebeneath while restricting access to said area from laterally adjacent jacket spaces, whereby to 120 125 130

promote an upward circulation with reference to said heated area throughout both sections of said reservoir jacket.

11. An internal combustion engine including the combination with a cylinder and a jacket open at their tops and secured together to comprise a unit, of a cylinder head removable from said cylinder and provided with a recess extending laterally therefrom, a reservoir section integrally connected with said head and including walls adapted to be removably registered with said jacket, one of said walls being formed to provide an outwardly opening recess in communication with the recess of said head through an aperture in said walls, and means for removably securing said reservoir section and head to said jacket and cylinder, said aperture in the wall of said section being adapted to receive a spark plug for the ignition of gases in the recess of said head.

12. An evaporation-cooled internal combustion engine including a cylinder provided with a jacket, an open reservoir in communication with said jacket above said cylinder, and means within said reservoir for obstructing a flow of cooling medium from one side of the reservoir to the other across said cylinder head.

13. An internal combustion engine including a cylinder provided with a jacket, a reservoir extending above said jacket and in communication therewith, a cylinder head for said cylinder provided with a laterally extending recess in communication with the cylinder, means for igniting fuel in said recess, and means for obstructing a flow of cooling medium across said reservoir in the direction of the portion of said head immediately above said recess.

14. An internal combustion engine including a cylinder provided with a jacket, a reservoir extending above said jacket and in communication with the space between said jacket and the cylinder, a cylinder head provided with a laterally extending recess in communication with said cylinder, and a web extending across said reservoir immediately above said cylinder head in a direction transverse to the direction of said recess.

15. An internal combustion engine including a cylinder provided with a jacket, a removable reservoir section comprising a vertical extension of said jacket and adapted to communicate with the space between said jacket and cylinder, a removable head for said cylinder provided with a recess in communication with the cylinder when the head is in place thereon, and ribs having a material vertical extension integrally connecting said head and said reservoir section, one of said ribs being disposed across said section and immediately above said head in a direction transverse to the direction of said recess, whereby a flow of cooling medium from

within said jacket to the area above said recess is encouraged.

16. An internal combustion engine including a cylinder provided with a jacket spaced therefrom and comprising a unit therewith, a reservoir section removable from said jacket and adapted to constitute an upward extension thereof, a cylinder head integrally connected with said reservoir section and removable therewith from said cylinder, said cylinder head being provided in its lower face with a recess in communication with said cylinder, integral ribs connecting said cylinder head and reservoir section, one of said ribs being extended across said head transversely to the direction of said recess, and means associated in part with said ribs for securing said cylinder head and reservoir section to said cylinder and jacket.

17. An internal combustion engine including a cylinder, a crank case, a water jacket extending from the crank case and about the cylinder, said water jacket and cylinder being open at their ends, an open reservoir section comprising walls adapted to register with the open end of said jacket and a recessed cylinder head integrally connected with said reservoir and constituting a unit therewith.

18. The combination with an evaporation-cooled engine having a cylinder and jacket, of a reservoir supported above the cylinder in communication with the space within the jacket, a head for said cylinder arranged to receive heat of combustion therefrom, and a baffle disposed across said reservoir immediately adjacent said head and adapted to intercept currents of cooling fluid local to said reservoir and flowing in the direction of heated portions of the head.

19. An internal combustion engine including the combination with a cylinder and a jacket open at their tops and secured together to comprise a unit, of a cylinder head removable from said cylinder and provided with a recess extending laterally therefrom, a reservoir section integrally connected with said head and including walls adapted to be removably registered with said jacket, one of said walls being formed to provide an outwardly opening recess in communication with the recess of said head through an aperture in said walls, and means for removably securing said reservoir section and head to said jacket and cylinder, said aperture in the wall of said section being adapted to receive a spark plug for the ignition of gases in the recess of said head and the portions of said head above the recess therein comprising an offset heated area adapted to induce upward movement of a coolant thereabove, whereby to promote coolant circulation throughout said jacket and reservoir section.
